His ATTORNEY.

UNITED STATES PATENT OFFICE

CARL SEVERIN, OF CLEVELAND HEIGHTS, AND LEO R. PETERS, OF CLEVELAND, OHIO,
ASSIGNORS TO GENERAL ELECTRIC COMPANY, A CORPORATION OF NEW YORK

CUT OUT FOR SERIES LAMPS

Application filed September 29, 1930. Serial No. 484,980.

Our invention relates to electric lamps adapted to be operated in series and more particularly to means whereby one or more of such lamps may be cut out upon failure thereof without extinguishing the remaining lamps of the series. Still more particularly, our invention relates to such means in combination with the other elements of an electric incandescent lamp. The features and advantages of our invention will appear from the following description of a species thereof and from the accompanying drawings. The scope of our invention is indicated in the claims appended hereto.

Nickel-chromium alloys or tungsten are particularly desirable for the wire 15 on account of their high resistance although there are many other metals and alloys which may be used. So-called nichrome is a nickel-chromium alloy which has a high resistance and is well known as a heating resistance element. It is preferred to have the resistance of the portion 15 of the cut-out fairly high so that the remaining lamps are not given too high a voltage. It may be desirable to provide beads 16 of insulating material, such as sodium silicate, which are placed around the leads and adjacent turns of the cut-out to hold the latter firmly in position.

In the drawings, Fig. 1 is an elevation of an electric incandescent lamp embodying our invention, and Fig. 2 is an elevation of a portion thereof on a larger scale.

The specific electric incandescent lamp illustrated in the drawings is of the type used for decorative purposes such as Christmas tree ornamentation. It comprises the bulb 10, the base 11 and sealed in the bulb is a mount comprising the leads 12 held firmly by the insulating bead 13 but extending therebeyond to support and afford electric conduction to the filament 14. Such lamps are usually mounted in sockets connected in series, for instance, a string of eight so connected is commonly used. When one or more of the lamps of the series burns out, the whole series would be extinguished but for a cut-out such as that of our invention, which is provided in each lamp. Such cut-outs are normally non-conducting but when the lamp fails, the voltage impressed across the cut-out is sufficient to break through the insulation normally provided thereby and a conductive path is provided through the lamp which has failed so that the other lamps may still burn.

As shown in the drawings, our cut-out in its preferred form comprises a spiral spring 15 of metal, the turns of which engage each of the leads 12 and make close contact therewith. The leads are of nickel or copper and have a film of oxide or other comparatively non-conducting material thereon. This film may be formed on the wire by heating and, in fact, sufficient oxide is formed on the leads during the fusion of the bead 13 there around.

What we claim as new and desire to secure by Letters Patent of the United States, is:—

1. In an electric lamp or similar device adapted to be used in series with other lamps or devices comprising a bulb and leads sealed therewith, a cut-out comprising a metal conductor of sufficiently high resistance to prevent substantial overloading of the other lamps or devices when it is in operation extending between said leads and making close contact with an insulating film capable of breaking down upon application of an abnormal voltage on at least one of said leads.

2. In an electric lamp or similar device comprising a bulb and leads sealed therewith, a cut-out comprising a spiral of high resistance metal extending between said leads and making close contact with an oxide film on at least one thereof.

3. In an electric lamp or similar device comprising a bulb and leads sealed therewith, a cut-out comprising a spiral spring metal conductor of high resistance having a pair of turns thereof gripping each of said leads and making close contact with the oxidized surface thereof.

4. In an electric lamp or similar device comprising a bulb and leads sealed therewith, a cut-out comprising a conductor consisting of nichrome extending between said leads and making close contact with an oxide film thereon.

5. An electric lamp or similar device comprising a bulb and leads sealed therewith, a cut-out comprising a spiral spring composed

of metal of high resistance and having a pair of turns thereof gripping each of said leads and beads of non-metallic insulating material fused around portions of said leads and metal spring to hold the latter firmly to said leads.

In witness whereof we have hereunto set our hands this 25th day of September, 1930.

CARL SEVERIN.
LEO R. PETERS.
